UNITED STATES PATENT OFFICE.

CARL SCRABIC, OF URBANA, OHIO.

SOUND REPRODUCER FOR TALKING MACHINES.

Application filed April 3, 1922. Serial No. 548,982.

To all whom it may concern:

Be it known that CARL SCRABIC, a citizen of the United States, residing at Urbana, in the county of Champaign and State of Ohio, has invented certain new and useful Improvements in Sound Reproducers for Talking Machines, of which the following is a specification.

This invention relates to an improved 10 sound reproducer or sound box for talking machines, and has for an object the provision of a sound box wherein the diaphragm will be mounted to vibrate within a closed chamber for the purpose of confining 15 within the sound box the sound disturbances created by the vibration of the diaphragm and preventing such disturbances from unduly escaping or becoming uselessly dissipated into the atmosphere without being 20 amplified, and to provide a common source of sound amplitude.

An object of the invention resides in mounting the diaphragm so that similar or exact conditions will prevail on both sides 25 thereof for the purpose of securing uniformity in the amplitude or pitch of the sound disturbances set up on opposite sides of the diaphragm, and to mount said diaphragm within an enclosed chamber formed 30 in the sound box having but a single outlet leading to the amplifier structure of the talking machine, through which outlet the sound disturbances of the diaphragm will find a common vent from the confines of the 35 sound box.

For a further understanding of the invention, reference is to be had to the following description and to the accompanying drawing, in which similar characters of reference denote like and corresponding parts 40 throughout the several views thereof.

In said drawing:

Figure 1 is a vertical longitudinal sectional view taken through the sound box 45 constructed in accordance with the present invention,

Figure 2 is a sectional view taken on the plane indicated by the line 2—2 of Figure 1,

Figure 3 is a sectional view on the line 3—3 of Figure 1, and

Figure 4 is a side elevation of the sound box.

Referring more particularly to the details of the invention the numeral 1 designates the improved sound box comprising

the present invention in its entirety. In the preferred form the sound box consists of a casing 2, which includes a rear wall 3 terminated in a forwardly extending flange 4, upon the outer edge of which is placed and secured a cover plate 5, the latter being secured as at 6 to the flange 4, and when connected as shown this casing will produce an enclosed air tight chamber 7 in which a diaphragm 8 will be supported for vibration. 60

The sound box is adapted to be connected with the outer end of a tone arm 9 and my preferred structure for effecting this connection consists in providing the outer end of a tone arm with a collar 10, suitably secured to the outer end of the tone arm 9. The said collar is provided with radially extending knife edge studs or trunnions 11, which are adapted to be received within bayonet slots 12, provided in an exterior sleeve 13, which is rigidly carried by the casing 2. The sleeve 13 terminates forwardly in an annular vertical flange 15, and an annular gasket 16 is arranged to be situated between the flange 15 and the wall 3 of the casing to prevent direct contact of adjoining metallic parts. Screws 17 are employed to directly connect the flange 15 with the wall 3. The forward ends of the collar 10 and sleeve 13 are provided with registering annular grooves, in which is seated a ring 18 of rubber or other resilient material, which is confined between the wall 3 and the fiber washer 19 also seated within the 80 grooves contained in the ring 18. By this construction it will be seen that the sound box may be detachably and flexibly connected with the outer end of the tone arm by first inserting the sleeve 13 over the collar 10 so that the studs 11 will be received within the longitudinally extending portions of the bayonet slots 12. Then, by rotating the sound box bodily about the tone arm 9, the said studs 11 will be positioned within the circularly disposed portions of the slots 12, thus securely locking the reproducer in an operative position upon the tone arm. When the studs 11 are in the circular portions of the slots 12 the ring 18 85

will be compressed, causing the same to exercise a sufficient degree of pressure to retain the studs in the slightly enlarged ends of the slots 12 and thereby preventing loss of adjustment on the part of the sound box. By forming the studs 11 in triangular or knife shaped form the same will act as trun- 90 95 100 105 110

nions, permitting of limited oscillation on the part of the casing 2 relative to the outer end of the tone arm. It will be observed that the sleeve 13 is formed in two parts, 5 the outer part serving to conceal the studs 11 and the slots 12, so as to present a neat and finished appearance to the sound box when the latter is in use. This construction is fully set forth in my co-pending application Serial Number 456,049 filed Mar. 28, 10 1921.

The gist of the present invention resides in mounting the diaphragm 8 within the casing 2 so that the diaphragm will be completely encased by the sound box and removed from disturbing extraneous conditions, means being provided for directing sound disturbances created on both sides of the enclosed diaphragm to a common outlet, 15 to insure uniformity in the amplitude of the sound disturbances set up on both sides of the diaphragm and in preventing undue dissipation of sound disturbances set up by the diaphragm by a peculiar structure for enclosing the latter.

To this end there is located within the chamber 7 a diaphragm plate 20, which includes a relatively thick body portion 21 and a reduced circumferential portion 22, 20 the axial part of the body portion 21 being formed with a rearwardly and longitudinally extending conduit 23, which is concentrically situated within and spaced from a similarly extending conduit 24, formed 25 with the wall 3, both of said conduits being concentrically disposed within the enlarged bell shaped mouth 25 of the collar 10, however, it will be observed that the adjoining walls of the mouth 25 and the conduits 23 and 24 are relatively spaced. To support the plate 20 within the casing, the wall 3 is provided with a plurality of inwardly extending screws 26, which pass through openings provided peripherally in the circumferential portion 22 of the plate 20, and fiber or other similar washers 27 surround the screws 26 and are interposed between the wall 3 and the plate 20, so as to space the latter from the wall 3 to provide a space 30 B which communicates with the space B' existing between the conduits 23 and 24, which space B' is in direct communication with the end of the tone arm 9. Cooperative with the plate 20 is a complimentary plate 28, which is provided with an enlarged body portion 29 having an axial opening or conduit 30 formed therein which is of the same size as the conduit 23 and is situated in registration therewith. The body portion 29 terminates near its periphery in a reduced wall 31 and is provided with a circumferential flange 32, arranged to receive the circumferential portion 22 of the plate 20, the said flange 32 being provided with 35 threaded openings 33 for the reception of

the ends of the screws 26, whereby when the latter are tightened into place the same will serve to securely retain the diaphragm plates 20 and 28 in assembled relationship. By effecting relative approach between the 70 plates 20 and 28 diaphragm gaskets 34 are compressed and retained in engagement with the circumferentially reduced portions 22 and 31 of said diaphragm plates, for the purpose of engaging with the perimeter 75 of the diaphragm 8, freely supporting the latter for vibration between said plates in a manner common to diaphragms of this character generally.

The outer plate 28 is spaced from the 80 cover or diaphragm closure 5, and similarly the flange 32 is spaced from the casing flange 4 for the purpose of producing spaces C and C' which communicate directly and freely with the spaces B and B'. The closure 5 is formed with a vertical depression 85 35 providing a groove 36, in which is positioned for movement the upper end of a stylus 37 having direct connection with the diaphragm 8. The lower end of the groove 90 36 is provided with a compressible ring 38, which surrounds the stylus 37 with a sufficient degree of firmness to permit of vibratory movement on the part of the stylus and yet to prevent sound disturbances from 95 passing out of the confines of the sound box. The stylus is pivotally mounted as at 39 upon the casing 2 and is adapted to receive the usual removable needle point 40.

By this construction it will be observed 100 that the diaphragm 8 will be so mounted within the sound box as to be spaced equidistantly from the diaphragm plates 20 and 28 so as to be capable of vibrating therebetween in conformity with the vibratory 105 movement of the stylus. By forming the conduit 23 and the opening 30 of the same diameter and in equally spacing the diaphragm from the plates 20 and 28 sound disturbances created by the vibratory movement of the diaphragm will be of equal 110 pitch or amplitude on both sides thereof for the purpose of enabling the sound disturbances to be properly equalized and to pass in unison through the common outlet 115 provided by the tone arm. I am aware that structures have been heretofore proposed wherein a diaphragm is positioned for vibration within a closed chamber, and I therefore do not claim such a construction 120 broadly, the present invention, however, not only encases a diaphragm but produces a structure wherein the sources of amplitude on both sides of the diaphragm are of substantially the same proportions and 125 wherein the sound waves are discharged through a common outlet, namely, the tone arm, of an associated amplifier.

What is claimed is:

In a sound reproducer for talking ma- 130

chines, an enclosed casing, a diaphragm supporting structure mounted within and spaced from the walls of said casing, said structure including a compartment, a diaphragm mounted within said compartment and spaced equidistantly from the walls thereof, an oscillating stylus extending into said casing for cooperation with said diaphragm, and conduits of equal diameter

formed in said supporting structure on both sides of said diaphragm, a third conduit carried by the supporting structure and disposed in concentric spaced relation with an adjacent conduit, all of said conduits being in communication with a common sound outlet. 10 15

In testimony whereof I affix my signature.
CARL SCRABIC.
